[57] CLAIM

The ornamental design for an I.V. flow control apparatus, substantially as shown and described.

DESCRIPTION

FIG. 1 is a perspective view of our new design for an I.V. flow control apparatus;

FIG. 2 is a back perspective view;

FIG. 3 is a side elevational view;

FIG. 4 is a front elevational view;

FIG. 5 is a side elevational view opposite FIG. 3;

FIG. 6 is a top plan view;

FIG. 7 is a back elevational view; and

FIG. 8 is a bottom plan view.
